No. 624,952.

Patented May 16, 1899.

W. T. LISENBY & A. R. BALDWIN.
AUTOMATIC GATE FOR ELEVATOR WELLS.

(Application filed July 26, 1897.)

(No Model.)

UNITED STATES PATENT OFFICE.

WILLIAM THOMAS LISENBY AND ALFRED RITCHIE BALDWIN, OF SPRINGFIELD, MISSOURI.

AUTOMATIC GATE FOR ELEVATOR-WELLS.

SPECIFICATION forming part of Letters Patent No. 624,952, dated May 16, 1899.

Application filed July 26, 1897. Serial No. 645,944. (No model.)

To all whom it may concern:

Be it known that we, WILLIAM THOMAS LISENBY and ALFRED RITCHIE BALDWIN, residing at Springfield, in the county of Greene and State of Missouri, have invented certain new and useful Improvements in Automatic Gates for Elevator-Wells; and we do hereby declare the following to be a full, clear, and exact description of the invention, such as will enable others skilled in the art to which it appertains to make and use the same.

Our invention relates to automatic gates for freight-elevator wells.

Our object is to provide a gate of simple and cheap construction which will be automatically opened by the elevator-car when ascending and approaching the landing and which will automatically close after the elevator-car has left the landing, whereby the landing will be protected, so that it will be impossible for persons employed about the elevator-well to fall down the same.

The invention consists of an automatic gate of improved construction, comprising certain improved features and novel combinations of parts appearing more fully hereinafter.

In the accompanying drawings, Figure 1 is a side elevation of an elevator-well and landing, disclosing our improved gate and a section of the elevator-car adapted to operate the same. Fig. 2 is a detail view showing the catch mechanism and the lifting-arm, and Fig. 3 is a detailed view showing the shifting mechanism.

The numeral 1 designates the framework of the elevator shaft or well, and 2 the landing.

Our improved gate is shown at 3, the same sliding in suitable guides on the framework. A rope 4, terminating in a freely-depending weight 5, is connected to the gate and runs over suitable overhead pulleys, said weight being of slightly-less weight than the gate, and hence adapted to permit the latter to descend slowly by gravity. A pull-rope 6 extends vertically from top to bottom of the well and adjacent to one corner of the elevator-car, said rope having its lower end fastened at 7 and its upper end passed over a pulley and provided with a freely-depending weight 8, the purpose of which is to keep the said rope taut at all times. On said rope there is

located a sleeve or button 9 at a suitable height above the landing. A bell-crank lever 10 is pivoted to the gate and has a hook 11 at the end of one of its arms, which loosely receives the rope 6, which is adapted to normally bear against the button 9, whereby the horizontal arm of said lever is kept normally elevated slightly by the action of the weight 8. A swinging lever 12 has its upper end pivoted to the gate and depends from said pivotal point. A connecting-rod 13 runs from the lower end of the swinging lever to the vertical arm of the bell-crank lever 10 and passes loosely through a swiveled button 14, said rod being provided with nuts 15 and 16 on opposite sides of said button for adjusting the length of the rod 13.

The numeral 17 designates a slide-catch having a U-shaped end 18, which embraces the swinging lever and is pivoted thereto, one end of said catch being beveled at 19. The other end works through a guide 20, connected with the gate, and has a roller 21 at its extremity, which bears against the upright at the side of the elevator-well as the gate ascends and descends. A lifting-arm 22, having a beveled or inclined end 23, is carried by the elevator-car, and said beveled end is adapted to engage with the free beveled arm 80 of the slide-catch when the elevator-car rises and to ride on said beveled portion when the elevator-car descends should the catch from any cause remain in the path of the lifting-arm. A tripping-cam 24 is connected to the upright of the framework at a suitable distance above the gate.

The operation is as follows: If the elevator-car is ascending and approaching the landing and it is desired to open the gate, a downward pull is exerted on the pull-rope 6, whereupon the horizontal arm of the bell-crank lever is allowed to drop and the slide-catch and swinging lever moved horizontally. This brings the free end of the slide-catch in line with the lifting-arm on the elevator-car, and said lifting-arm thereupon engages with the slide-catch and raises the same, which causes the gate to be lifted until the roller of the catch lies immediately below the tripping-cam, at which time the elevator-car is at the landing and the gate is opened. As the ele-

vator-car ascends beyond the landing the roller rides on the tripping-cam, thereby disengaging the slide-catch from the lifting-arm, and the gate then drops slowly by gravity. 5
 5 Should the elevator-car descend from the landing after having arrived thereat, the gate will follow the elevator-car down by its own gravity and the arm of the bell-crank lever will be held slightly elevated by the rope 6, so 10
 10 that the slide-catch is held normally retracted. Unless, therefore, the pull-rope is actuated the slide-catch remains out of the path of movement of the lifting-arm, and hence the gate will not be raised. When the elevator-car descends to the landing, the gate remains closed. Therefore, as the gate is lifted by hand, as it leaves the landing the slide-catch drops into the path of the lifting-arm, and as the gate is raised the free beveled end 15
 15 of the catch 19 rides over the beveled part of the lifting-arm 23 and drops in above said lifting-arm, thus holding the gate open.

Having thus described the invention, what we claim as new, and desire to secure by Letters Patent, is—

- 25 1. The combination with a movable gate, of a catch thereon, an elevator-car, a lifter thereon adapted to engage with the catch, and means for keeping said catch normally retracted out of the path of movement of the lifter, said means being capable of government from the elevator-car to cause the catch to lie in the path of movement of said elevator-car.
- 30 2. The combination with a movable gate, of a catch thereon, an elevator-car, a lifter thereon adapted to engage with the catch, means for keeping said catch normally retracted out of the path of movement of the lifter, said 30 means being capable of government from the elevator-car to cause the catch to lie in the path of movement of said elevator-car, and a trip adapted to break the engagement of the catch with the lifter when the gate is opened
- 35 40 45 40 45 and the elevator-car has passed beyond the same whereby the gate is permitted to close.
- 50 3. In a device of the class described, the combination with a gravity-actuated gate and a movable catch thereon, of an elevator-car, a lifter thereon adapted to engage with the catch, a pull-rope located adjacent to the elevator-car and engaging with and adapted to hold the catch normally retracted out of the path of movement of the lifter, and a trip

adapted to engage with the catch and retract 55 the same out of engagement with the lifter after the elevator-car has ascended beyond said gate whereby the gate is released and permitted to close by gravity.

4. In a device of the class described, the combination with a gate, of a slide-catch thereon, a lever operatively connected with the slide-catch, and constantly exerting a tendency to project the same into operative position, an elevator-car, a lifter carried thereby, a pull-rope, and means for drawing the same in one direction, and said rope having a device adapted to normally engage with the lever aforesaid whereby the slide-catch is kept retracted, and a trip adapted to engage with 70 the slide-catch after the elevator-car has passed beyond the landing, the retraction of said pull cord or rope releasing the lever and causing a projection of the slide-catch into the path of movement of the lifter. 75

5. In a device of the class described, the combination with a vertically-movable gate, of a counterbalancing device therefor, a swinging lever pivoted to the gate, a slide-catch pivoted to the lever and provided with 80 a roller on its end, a bell-crank lever pivoted to the catch and provided with a hook on the end of one arm, a connecting-rod leading from the other arm to the free end of the swinging lever, an elevator-car, a lifter-arm carried thereby adapted to engage with the slide-catch, a pull-rope having one end secured and its other end provided with a freely-depending weight whereby it is maintained taut at all times, said pull-rope passing through the hook 90 on the bell-crank lever, a button on said rope adapted to engage with the arm on the bell-crank lever and to hold the same raised whereby the catch is normally held in retracted position, and a trip adapted to engage with the 95 roller after the gate has been opened and the elevator-car has ascended beyond the landing, said pull-rope when actuated releasing the bell-crank lever and permitting the projection of the catch into the path of the lifter. 100

In testimony whereof we have signed this specification in the presence of two subscribing witnesses.
